FASTENING MEANS FOR CRUSHING-ROLLS.

1,181,304.

Specification of Letters Patent.

Patented May 2, 1916.

Application filed September 30, 1915. Serial No. 53,423.

To all whom it may concern:

Be it known that I, JESSE GOFF, a citizen of the United States, residing at Webb City, in the county of Jasper and State of Missouri, have invented a new and useful Fastening Means for Crushing-Rolls, of which the following is a specification.

This invention has reference to crushing mills of the roller type, and its object is to provide rollers with active portions readily replaceable in a minimum time at a minimum expenditure of labor.

Roller mills of the type of the present invention are employed in mines for crushing dirt, and each roller comprises a hub portion and a rim or shell portion, the latter being the part which is subjected to the wearing action of the dirt and which requires renewal at frequent intervals. Ordinarily the peripheral or shell portion is keyed on to the hub portion of the roller, and in the case of the master or driving roller, it is in the ordinary construction necessary to remove the driving gear so that the whole procedure consumes several hours' time and an excessive amount of labor, during which time the mill cannot do any work.

In accordance with the present invention the shell portion and the hub portion have a taper fit and are connected together by a key construction at all times readily accessible and of a nature providing a cushion connection which avoids breakage of the outer shell.

There are usually three sets of rollers to a mill and the shells wear in from two to three weeks, while the driving gear weighs from 400 to 600 pounds. With the arrangements previously used the time required in changing shells is not less than five hours. With the present invention the same operation is performed in from one to one and one-half hours, whereby there is a material saving in time and labor.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be

changed and modified so long as such changes and modifications come within the scope of the appended claims.

In the drawings:—Figure 1 is a side elevation of a pair of rollers and their mountings, with the rollers constructed in accordance with the present invention. Fig. 2 is a section on the line 2—2 of Fig. 1. Fig. 3 is a section on the line 3—3 of Fig. 1, but drawn on a larger scale. Fig. 4 is a perspective view of one of the cushion-like wedges employed. Fig. 5 is a perspective view of a cam-shaped gripping member.

Referring to the drawings there is shown a frame 1 without any attempt to show any particular structure thereof, such frame serving merely the purpose of a supporting frame and a carrier for journal bearings 2, 3, the latter being movable toward and from the journal bearings 2 and urged toward the journal bearings 2 by elastic means such as springs 4.

Mounted in the journal bearings 2 is a shaft 5 carrying a taper hub 6 forming part of a crushing roll. The bearings 3 carry a shaft 7 on which is mounted a hub 8 forming part of another crushing roll coating with the first-named crushing roll. The shaft 5 is provided with a gear wheel 5^a by means of which the roller mounted on the shaft 5 is rotated to cause the crushing of material introduced between the two rollers, the spring permitting the rollers to separate to any necessary degree.

The two rollers may be in most particulars alike, and hence similar parts in the two rollers are referred to by the same reference characters. The taper hub 6 carries a corresponding tapered shell 9 having marginal flanges 10 on opposite sides. The hub 8 carries a taper shell 11, but free from side flanges, the shell being exteriorly cylindrical and entering between the flanges 10 of the shell 9. Such shells constituting the outer renewable members of the rollers act upon the dirt to be crushed, which dirt is introduced between the rollers and it may be assumed that the rollers rotate in opposite directions, as indicated by the arrows in Fig. 1. The smaller ends of the hubs 6 and 8 are directed toward that side of the machine remote from the gear wheel 5^a. The result of this is that either shell 10 or 11

may be removed from the respective hub 6 or 8 by moving it lengthwise of the hub toward the small end of the latter and the taper surfaces are very readily disconnected.

In order to hold the shells on the respective hubs each hub has at its small end oppositely-disposed ears 12 on diametrically opposite sides of its axis, and these ears are provided with radial holes each designed to receive a stem 13 projecting eccentrically from a cam 14 having teeth 15 or other similar biting surfacing. The ears 12 are so disposed that when the stems 13 are seated therein the cam blocks are opposite the corresponding face of the shell 9 or 11, as the case may be. There are also provided elongated wedges 16 which may be made of wood, the other parts which have been described being made of metal. The wedges 16 are driven between the cam blocks 14 and the corresponding face of the shell 9 or 11, so that each cam block is turned on the axis of the stem 13 in the direction to force the teeth 15 into the wooden wedge 16, thus holding the latter in place by positive engagement since any frictional engagement between such parts would be very small. The other face of the wedge, however, has extended frictional engagement with the corresponding face of the shell of the roller, so that there is practically no liability of the wedge loosening, and so long as the wedge cannot move on the shell of the roller, the cam block cannot loosen. Furthermore, the cam block and wedge are so arranged that any tendency of the shell to turn on the hub during the operation of the roller is exerted in a direction to force the wedge more firmly into the clamping position and to turn the cam block in a direction to press with greater force upon the wedge. Since the wedge is of wood it is of a far more elastic nature than the shell, or the cam block, and consequently the wooden wedges serve as cushions yielding to some extent to strains tending to burst the shells. The result is that the shells are preserved from injury by the cushioning action of the wooden wedges.

When the shells have become so worn as to necessitate replacing them, which condition is reached in from two or three weeks of use, there is no need of removing the gear 5^a from the shaft 5, nor the hub 6 from said shaft, nor the hub 8 from the shaft 7. All that is needed to remove the shafts from their bearings is to lift the rollers and shafts therefrom and then by loosening the wedges 16 such wedges and the cam blocks 14 may be entirely removed, after which it is an easy matter to loosen the shells from the hubs because of the tapering connection between the two. New shells may be substituted, the cam blocks returned to position, and the wedges 16, or new wedges 16, driven into place when the mill is ready for

use. In actual practice this may be performed in from an hour to an hour and a half in a mill containing three sets of rollers instead of consuming no less than five hours where the rollers are keyed into place 70 in the ordinary manner.

What is claimed is:—

1. A roll for a crushing mill, comprising a taper hub, and a shell with a taper seat for the hub, the hub at its smaller end having exterior lugs with passages therethrough, rotatable cam heads carried by the lugs, and wedges fitting between the cam heads and the corresponding face of the shell of the roll. 75

2. A roll for a crushing mill, comprising a taper hub, and a shell with a taper seat for the hub, the hub at its smaller end having exterior lugs with passages therethrough, rotatable cam heads carried by the lugs, and wedges fitting between the cam heads and the corresponding face of the shell of the roll, the cam heads having the cam surfaces roughened to bite into the wedges. 80

3. A roll for a crushing mill, comprising a taper hub, and a shell with a taper seat for the hub, the hub at its smaller end having exterior lugs with passages therethrough, rotatable cam heads carried by the lugs, and wedges fitting between the cam heads and the corresponding face of the shell of the roll, the cam heads having the cam surfaces roughened to bite into the wedges, and said wedges being constructed of wood, with the other portions of the roll constructed of metal. 90

4. A roll for crushing mills, comprising a hub member and a shell member with their meeting parts axially tapered to fit, connecting means on one end face of one member and extending over the corresponding end face of the other member, and wooden members lodged between the respective connecting means and the adjacent face of the said other member, whereby the wooden members serve as cushioning devices responsive to forces exerted lengthwise of the axis of the roll. 105

5. A roll for rolling mills comprising a taper hub and an exterior shell having a corresponding interior taper seat on the hub, and said hub having exterior wedges and securing means therefor to hold the shell in place. 115

6. A roll for crushing mills comprising a taper hub and a shell with an interior taper fitting the hub, said hub having exterior ears at the smaller end, cam blocks removably carried by and rotatable in the 125 ears and extending over the corresponding face of the shell, and wedges adapted to enter between the cam blocks and the corresponding face of the shell.

7. A roll for rolling mills comprising a 130

taper hub, an exterior shell with an interior taper fitting the taper of the hub, and said hub having exterior lugs at its smaller end, cam blocks with eccentrically disposed stems removably seated in the lugs and extending over the corresponding face of the shell with the cam portions of the cam blocks roughened, and cushioning wedges for introduction between the cam blocks and 10 the corresponding face of the shell, the

wedges being of a material into which the roughened portions of the cams will bite.

In testimony that I claim the foregoing as my own I have hereto affixed my signature in the presence of two witnesses.

JESSE GOFF.
